UNITED STATES PATENT OFFICE.

THEODOR VON BAUER, OF BURGEL, TURINGEN, GERMANY, AND BERNHARD ZWILLINGER, OF NEW YORK, N. Y.; SAID VON BAUER ASSIGNOR TO SAID ZWILLINGER, KLARA ZWILLINGER ADMINISTRATRIX OF SAID BERNHARD ZWILLINGER, DECEASED.

SOLE-HEATED COKE OVEN.

Application filed March 3, 1921. Serial No. 449,444.

To all whom it may concern:

Be it known that we, THEODOR VON BAUER and BERNHARD ZWILLINGER, citizens of the Republic of Germany and the United States, respectively, residing at Burgel, Turingen, Germany, and 520 West 188th Street, New York, New York, respectively, have invented new and useful Improvements in Sole-Heated Coke Ovens, of which the following is a 10 specification.

This invention relates to a sole-heated coke oven preferably with side wall heating and with by-product recovery and has for its 15 objects to improve the construction of the oven, to preheat the air for combustion to a higher degree than heretofore, thus increasing the quantity of surplus gas produced; to provide a more intense heat at both fronts of the oven so as to counter- 20 balance the losses due to radiation of heat thru the oven doors; to change the method of heating at will from a direct fired oven in which the products of distillation are used for heating the sole of the oven, without re- 25 covering the by-products, to an oven with by- product recovery, thus enabling the oven at will to be operated either directly or indirectly, the change over being made without alteration of the oven structure and in a 30 very short time.

Other objects of the invention will appear from the following specification, the invention consisting in the novel features and construction of parts and their combination as 35 hereinafter described.

Despite the progress which has been made in the development of the high and narrow by-product chambered oven, especially that resulting in the increase in tonnage, i. e. 40 carbonizing large quantities in a comparatively short time, the modern by-product coke oven is encumbered with a number of substantial disadvantages. First of all its efficiency in tonnage has led to great complexity in the construction of the oven which 45 in turn necessitates very large expenditures for material and labor and also increases the cost of operation and maintenance. Furthermore the ability of the oven to carbonize certain coals, which expand in the process of 50 coking, is not only limited, but this becomes

impossible owing to the fact that such expanding coke is liable to jeopardize the oven structure so that certain coals can be used only in limited quantities and in a mixture 55 with shrinking coals, which again involves higher operating and initial costs. Inasmuch, also, as in the production of crude gases the by-products are partly decomposed in the crevices formed between the shrinking 60 coke and the highly heated side walls, the modern by-product oven is lacking in efficiency in this direction.

For a considerable time, the endeavor has been made to carbonize coal not readily cokable and also to utilize the space within the oven chamber by exerting a pressure by 65 mechanical means on the tops of the coal charges in these high and narrow ovens, but this endeavor has been without success. Even 70 a heavy pressure exerted on a high coal column affects the material to a small depth only and for this reason such attempts to compress the charge into a smaller space have been found unsatisfactory 75

The present invention has for another object to eliminate these disadvantages as will appear more fully hereinafter.

Referring to the accompanying drawings which form part of this specification and in 80 which like figures and characters refer to like parts,

Fig. 1 is a vertical section thru the oven chamber on line A—A of Figs. 2 and 4.

Fig. 2 is a horizontal section thru the combustion flues on line B—B of Fig. 1 and Fig. 4.

Fig. 3 is a vertical section thru the side wall combustion flue on line C—C of Fig. 2 and Fig. 4.

Fig. 4 is a transverse vertical section on an enlarged scale on line D—D of Fig. 1 and Fig. 3.

Fig. 5 is a horizontal section on line E—E of Fig. 3 and Fig. 4 showing the air supply 95 conduits.

As shown in Figs. 1, 2, and 3, the gas for heating the ovens which may come from the gasholder where it has been stored, after the by-products have been removed from the gas, is led to gas mains 1 and 2 at each 100 end of the oven, there being a separate main

for each end of the oven. From the gas main 1 the gas is led by means of branch pipes 3 and nozzles 4 to a gas collecting channel 5 from which the gas mixed with heated air, as will presently be described, passes into the combustion flues 6 underneath the sole of the oven chamber. The admission of the gas to the collecting cross channel 5 and therefore to the sole flues, is regulated and controlled by means of a series of valves 7, a series of the valves being preferably connected to a rod 8 which in turn is operated by the lever 9. In this way the actuation of the lever will simultaneously control a number of the gas valves. The gas main and valves are preferably located in a pit but the lever is very accessibly located and easily visible.

In the best embodiment of the invention use is made of a plurality of collecting cross channels as for example two at each end of the oven, separated from each other at the middle by a partition 10.

In accordance with the invention means are provided for highly heating the air to be mixed with the gas which mixture is then burnt in the combustion flues. The suction for drawing the air and the waste gases thru and from the oven may be a stack or a ventilating fan at the discharge end of the flue system (not shown).

In the embodiment of the invention illustrated the air for heating the combustion flues enters the oven thru openings 11, thus passing into air supply conduits 12, one air supply conduit being preferably arranged underneath each combustion flue. The air inlet opening may be closed by means of a flap 13 and these flaps for the openings may be connected by a crank shaft 14 as shown in Fig. 5, the shaft being operated by a crank 15 at one end. The air for combustion is preliminarily preheated in passing thru the air conduits 12 by the heat conducted from the lower part of the combustion flues, which heat would otherwise be more or less lost in the ground. After such preheating the air ascends thru vertical passageways 16 and passes into the heating twy whole 17. These heating twy whole may be variously constructed and located. In the embodiment of the invention illustrated, one set of twy whole form part of the structure constituting the heating floor of the oven. The side twy whole extend underneath the side wall combustion flues. As shown, the walls of the twy whole of the oven bottom separate the combustion flues from each other thus providing a plurality of separate and independent combustion flues forming a heating floor parallel to each other and extending in the direction of the length of the oven chamber beneath its sole. The heating floor is of uniform thickness. These twy whole walls formed of bricks 18 are provided at

their outlet ends, adjacent the ends of the oven chambers, with one or more side outlets 19, and also with discharge outlets 20. Thru the side outlets 19 the heated air impinges substantially at right angles upon the stream of incoming gas for combustion and an intimate mixture of gas and air takes place, comparatively small quantities being mixed at a time resulting however in a thoro heating of the entire area. The air having passed in rather thin streams thru the air twy whole and being subjected to the intense heat from both sides of the combustion flues, will escape from the side outlets and from the discharge outlets in a highly heated condition, which may exceed one thousand degrees centigrade. The heated air from the twy whole passing thru its discharge outlet 20 enters the collecting front gas channel 5 into which fresh gas is fed from the gas mains 1, thus producing a more intense heat at the front ends of the oven, which is desirable in order to counterbalance the losses caused by the radiation of heat at the oven doors, thereby obtaining a uniform heat thruout the floor of the oven, and thus producing a uniform quality of coking thruout the charge.

In the best embodiment of the invention the heating system for each oven chamber is divided into a plurality of groups so as to simplify the discharge of the waste gases from the combustion flues and to reduce the number of valves used to control the heating flues at their discharge ends, thus regulating the draught by a smaller number of accessibly located valves than there are heating flues.

In the form of the invention illustrated, the heating floor flue system for each oven chamber is divided into four groups. A division wall 21 separates the flues into two groups, one underneath the front and the other underneath the rear of the oven chamber, and each of said groups is divided into two subordinate sets by division wall 22, thus forming four sets of flues to the right and left of the central longitudinal axis of the oven chamber floor.

The side wall combustion flues form part of the said groups and sets of flues. The combustion flues are connected at their ends to collecting channels 23, 24, 25, 26 respectively. The collecting channels 23 and 24 communicate with a short vertical flue 27 and the collecting channels 25 and 26 communicate with a short vertical flue 28. The vertical flues 27 and 28 discharge into the waste gas main 29 which is common to a bank or plurality of oven chambers. The waste gas main is preferably located underneath the oven chambers and extends transversely thereof midway between the ends of the ovens. Slide valves 30 sliding in guide ways 30^a are provided for the vertical flues

27 and 28, thus controlling the two sets of flues which discharge into the channels 23 and 24 and the two sets of flues which discharge into the channels 25 and 26. These 5 slide valves may be screwed up and down to entirely cut off or to regulate the discharge of the waste gases and thus control the draft. From the waste mains 29 the products of combustion pass into a chimney or to a suction fan (not shown). The construction of the side heating walls of the oven is more particularly illustrated in Fig. 3. The air for combustion passes thru the preheating passage 32 which may be closed or regulated 10 by a valve 33 controlling the air inlet. This passage receives some heat from the radiating oven walls. From the passage 32 the air by means of short connecting passage 31 passes into the air preheating passage 34 which receives its heat from the side wall combustion flue 35, the air passing into the combustion flue 35 through one or more openings 36, which may be placed as indicated or in the end wall of the flue 34. The 15 preheated air for combustion is mixed with incoming gas in one of two ways according to whether the oven is to be heated by the indirect or by the direct method. If heated by the indirect method, the gas is taken from the supply mains 1, 2, the gas from these mains passing through branch pipes 37 controlled by valve box 38, the valves being operated by handle 9. The gas enters the supply mains from a gasholder after it has 20 been freed from the by-products. The fresh gas and air pass into the side wall combustion flue 35 by means of the orifice 39 and the openings 36 respectively. The discharge ends of the side wall combustion flues communicate with the waste main 29 through connecting passageways 40. These passageways communicate with the vertical flues 25, 28 and are opened and closed by the previously described slide valves 30. 25 If the oven is to be fired by the direct method, that is to say by crude gases coming directly from the oven chamber, the admission of gas from gas mains 1 and 2 is stopped by suitably moving the lever 9 and thus shutting the gas valves. The slide valves 41, which closed the opening to the combustion flues when the oven was operating on the direct method, are now moved inwardly, thus establishing a communication with the interior of the oven chamber, above the charge, through ports 42 into the side wall passageways 43, and the combustion chambers of the side wall heating flues and of the bottom heating flues of the oven. This communication is effected by means of the vertical passageway 44 in the side heating wall and the cross channel 5 at the front of the heating floor. 30 The stability of the side heating walls is improved and the distribution of the heat in the side wall combustion flue is bettered by means of a row of staggered, binding stones 45 which connect the two faces of the combustion flue. In the application of heat, the side walls will not only increase the 35 heating surface of the oven but will also assist in shortening the time of operation and produce a hard, dense coke on the sides of the charge. 40 When the horizontal slide 41 is opened and the gas nozzles 4 are closed the oven is operated by the direct method for the production of coke only. It will be observed that in addition to simplicity of construction, a considerable flexibility of operation is obtained and a rapid change from direct to indirect heating or vice versa is possible and in fact without reconstructing the plant and without disturbing its construction in any way. By this quick, changeable control 45 and operation of the oven, coal of wide difference of character can be carbonized in the same oven so that the oven becomes a combination oven which can be operated in either way. In the event that the oven is charged with a coking coal low in volatiles, in which case it would prove unremunerative to install a by-product plant, or in case a rich volatile coal is being carbonized with recovery of by-products and it is for any temporary reason preferred to produce coke and heating and power gas only, the heating of the system is effected by the direct method. 50 The by-products are discharged from the oven chamber by suitable means. A tar main may be used, but the crude gas suction channels 46, 47, as illustrated, are preferred. These will form the subject matter of a separate patent application. Each consists of an arched culvert forming part of the oven structure and extending transversely over the oven chamber. Each is provided with a horizontal passageway 48 communicating by means of a vertical passageway 49 with the oven chamber 50. This vertical passageway is provided with a cast iron slide valve 51 which may be moved up and down by rack and pinion, so as to open and close communication between the oven chamber and the crude gas suction channel. From the gas suction channel the gases pass to the condensing plant. The crude gas suction channels form part of the ovens. They are made of poor heat conducting material and are well protected from all sides against the influence of the atmosphere. Condensation cannot take place within them, since they remain hot and are not cooled, and therefore substantially the entire amount of crude gases from all the ovens is conducted to the condensation plant where the separation of tar, ammonia, etc. is accomplished. 55 The oven sole is gas and air tight. The joints between the fire bricks forming the 60

130

sole are disposed so that the expansion is taken care of in each oven independently. The sole plates rest upon the twyer bricks. The latter have a solid top and leave sufficient space for joints between the sole plates so that expansion can take place in both length and width. The twyer bricks are provided with tongues and grooves to prevent short circuiting of the air between the joints. The oven chamber is preferably constructed and crowned by two arches so as to give the oven a high stability. The roof is strong partly due to its enclosure of the crude gas channels and insulates the oven chamber with respect to the surrounding atmosphere. It is provided with the usual charging openings 52.

The operation of the ovens will be clear. But because of the horizontal charge, the charge may be compressed after leveling it in the usual way. Such compressions may take place from iron rollers which can be either attached to the leveling machine or worked separately. These iron rollers can be moved back and forth upon the coal charge, thus compressing it to a considerable degree, since the coal layer is comparatively speaking, of moderate thickness. The entire charge may thus be compressed, thereby increasing not only the tonnage but also improving the quality of the coke.

The gases obtained from the oven are undecomposed and unimpaired as to quality, yielding a higher candle power and more British thermal units than the average vertical oven. Lifting and lowering the doors is easy of accomplishment owing to the low height of the oven chamber. The charge being flat, less breeze is formed when the coke is discharged, and the operation of quenching is less difficult and more thorough in its effect.

When charging the ovens, one may open the port to the side flues and thus lead the crude gases into the flues underneath the ovens, thus avoiding the smoke and disagreeable effects ordinarily produced in other ovens, during the charging period.

We claim:

- 50 1. In a sole heated coke oven having an elongated, sealed oven chamber, with doors at both ends and adapted to receive the charge in a horizontal layer, the combination of a plurality of combustion flues forming a floor for heating the oven chamber, longitudinal and transverse partitions separating the combustion flues into four groups, and two valves for controlling the discharge outlets of said groups and means for supplying air and gas at both fronts of the oven.
- 55 2. In a sole heated coke oven adapted to receive the charge in a horizontal layer, the combination of a plurality of combustion flues forming a floor of uniform thickness for heating the oven chamber, longitudinal and transverse partitions separating the combustion flues into four groups, and two valves for controlling the discharge outlets of said groups and means for supplying air and gas at both fronts of the oven.
- 60 3. In a low chambered sole heated coke oven with a sealed coking chamber, the combination of a plurality of combustion flues forming the floor of the oven, means for supplying air and gas for combustion to both fronts of the oven, longitudinal and transverse partitions separating the combustion flues into four groups, a transverse waste gas collecting channel for each group, arranged at the discharge level of said flues, vertical flues leading to the collecting channels, a waste main communicating with said vertical flues and slides for controlling said vertical flues.
- 65 4. In a low-chambered sole heated coke oven with a sealed, elongated coking chamber with doors at both ends, the combination of a plurality of combustion flues forming the floor of the oven chamber, longitudinal and transverse partitions separating the combustion flues into four groups, means for supplying air and gas at both fronts of the oven, and a waste main for receiving the products of combustion from the combustion flues.
- 70 5. In a sole heated coke oven with a coking chamber sealed against the admission of air, adapted to receive the charge in a horizontal layer, the combination of a plurality of combustion flues for heating the sole of the oven, a plurality of air supply conduits arranged in the base of the oven beneath the combustion flues, said conduits having open ends leading into the atmosphere, valves for said conduits, levers for regulating the valves, air heating twyers between said combustion flues, passages connecting said air preheating passages with said twyers, said twyers being provided with ports for discharging highly preheated air into the combustion flues, and means for supplying air and gas for combustion at both fronts of the oven.
- 75 6. In a sole heated coke oven with a coking chamber sealed against the admission of air and adapted to receive the charge in a horizontal layer, the combination of a plurality of combustion flues running lengthwise of the sole of the oven for heating it, a plurality of air supply conduits, arranged beneath the combustion flues, one end of said conduits being in communication with the atmosphere, air heating twyers arranged between said combustion flues, said twyers communicating with said conduits and provided with a port for discharging preheated air into the combustion flues.

70 7. In a sole heated coke oven, air preheating twyers lying between adjacent flues, means for supplying air and gas at both fronts of the oven, to said flues and twyers, longitudinal and transverse partitions separating the combustion flues into four groups, and valves for controlling the discharge outlets of said groups.

75 8. In a low chambered sole heated coke oven with a sealed coking chamber, the combination of a plurality of combustion flues forming the floor of the oven, means for supplying air and gas for combustion to both fronts of the oven, longitudinal and transverse partitions separating the combustion flues into four groups, a transverse waste gas collecting channel for each group, arranged at the discharge level of said flues, vertical flues leading to the collecting channels, a waste main communicating with said vertical flues and slides for controlling said vertical flues.

80 9. In a low-chambered sole heated coke oven with a sealed, elongated coking chamber with doors at both ends, the combination of a plurality of combustion flues forming the floor of the oven chamber, longitudinal and transverse partitions separating the combustion flues into four groups, means for supplying air and gas at both fronts of the oven, and a waste main for receiving the products of combustion from the combustion flues.

85 10. In a sole heated coke oven with a coking chamber sealed against the admission of air, adapted to receive the charge in a horizontal layer, the combination of a plurality of combustion flues for heating the sole of the oven, a plurality of air supply conduits arranged in the base of the oven beneath the combustion flues, said conduits having open ends leading into the atmosphere, valves for said conduits, levers for regulating the valves, air heating twyers between said combustion flues, passages connecting said air preheating passages with said twyers, said twyers being provided with ports for discharging highly preheated air into the combustion flues, and means for supplying air and gas for combustion at both fronts of the oven.

105 11. In a sole heated coke oven with a coking chamber sealed against the admission of air and adapted to receive the charge in a horizontal layer, the combination of a plurality of combustion flues running lengthwise of the sole of the oven for heating it, a plurality of air supply conduits, arranged beneath the combustion flues, one end of said conduits being in communication with the atmosphere, air heating twyers arranged between said combustion flues, said twyers communicating with said conduits and provided with a port for discharging preheated air into the combustion flues.

flues, and means for supplying air and gas for combustion at both fronts of the oven.

7. In a sole heated coke oven with a coking chamber sealed against the admission of air and adapted to receive the charge in a horizontal layer, the combination of a plurality of combustion flues running lengthwise of the sole of the oven for heating it, a plurality of air supply conduits arranged

10 beneath the combustion flues, one end of said conduits being in communication with the atmosphere, air heating twyters having vertical sides which form the walls of the combustion flues, said twyters communicating

15 with said conduits and provided with one or more ports for discharging preheated air into the combustion flues, and means for supplying air and gas for combustion at both fronts of the oven.

20 8. In a sole heated coke oven with a coking chamber sealed against the admission of air and adapted to receive the charge in a horizontal layer, the combination of a plurality of combustion flues running length-

25 wise of the sole of the oven for heating it, partitions separating the combustion flues into a plurality of groups, a transverse waste gas collecting channel for each group, communicating with the combustion flues

30 of the group, air heating twyters arranged between the combustion flues, said twyters communicating with the atmosphere and provided with one or more ports for discharging preheated air into the combustion flues, means for supplying gas to the combustion flues at both fronts of the oven and a waste main into which the products of combustion are discharged from the waste gas collecting channels.

35 9. In a low chambered sole heated coke oven provided with an oven chamber sealed against the admission of air, a heating floor for the sole of said oven comprising a plurality of combustion flues, means for sup-

40 pllying gas to said flues at both fronts of the oven, a plurality of air supply conduits arranged beneath the combustion flues, and having open ends leading into the atmosphere, valves for said conduits, a plurality of air twyters arranged between the combustion flues and communicating with said conduits, the walls of the twyters being formed of hollow bricks, the bricks at the discharge end of the twyters being provided with one

45 50 or more ports for discharging air into the adjacent combustion flues, said air ports for adjacent flues being staggered with relation to each other.

55 10. In a low chambered sole heated coke oven provided with an oven chamber sealed against the admission of air and adapted to receive the charge in a horizontal layer, the combination of an oven chamber, a discharge main for the by-products, said oven

60 chamber provided with one or more ports

for delivering gases directly to the combustion flues, a plurality of combustion flues forming the sole of the oven, side wall combustion flues for the sides of the oven, passages connecting said sole flues with the side 70 flue, a passageway connecting said port or ports with the side combustion flues, a valve for said passageway and means for supplying air and gas to the combustion flues from both fronts of the oven, whereby the oven 75 may be operated either directly or indirectly.

11. In a sole heated coke oven with a coking chamber sealed against the admission of air and adapted to receive the charge in a 80 horizontal layer, the combination of a plurality of combustion flues running lengthwise of the sole of the oven for heating it, air heating twyters having vertical sides which form the walls of the combustion 85 flues, said twyters provided with one or more ports for discharging preheated air into the combustion flues, and means for supplying air and gas for combustion at both fronts of the oven.

90 12. In a sole heated coke oven with a coking chamber sealed against the admission of air and adapted to receive the charge in a horizontal layer, the combination of a plurality of combustion flues running length- 95 wise of the sole of the oven for heating it, a transverse partition for separating the flues into groups, each group shorter than the length of the oven, air heating twyters having vertical sides which form the walls 100 of the combustion flues, said twyters provided with one or more ports for discharging preheated air into the combustion flues, and means for supplying air and gas for combustion at both fronts of the oven.

105 13. In a sole heated coke oven with a coking chamber sealed against the admission of air and adapted to receive the charge in a horizontal layer, the combination of a plurality of combustion flues running length- 110 wise of the sole of the oven for heating it, air heating twyters having vertical sides which form the walls of the combustion flues, said twyters provided with one or more ports for discharging preheated air 115 into the combustion flues, transverse gas collecting channels at each front of the oven, and means for supplying air and gas for combustion at both fronts of the oven.

120 14. In a sole heated coke oven adapted to receive the charge in a horizontal layer, the combination of a plurality of combustion flues forming a floor for heating the oven, means for supplying air and gas at both fronts of the ovens to said flues, and means 125 communicating with the oven chambers above the charge for leading the distilled gases to said flues at both fronts of the oven when it is desired to operate the oven directly.

15. In a sole heated coke oven having an elongated oven chamber adapted to receive the charge in a horizontal layer, a plurality of combustion flues forming a floor for heating the oven, cross-channels at both fronts of the oven communicating with said combustion flues, and means for supplying

air and gas to the heating flues and to said cross-channels, at both fronts of the oven.

In testimony whereof, we have signed our names to this specification.

THEODOR von BAUER.
BERNHARD ZWILLINGER.
